Specification for Design.

Patented Aug. 9, 1921.

Application filed November 8, 1920. Serial No. 422,744. Term of patent 7 years.

To all whom it may concern:

Be it known that I, WILLIAM F. BEATTY, a citizen of the United States of America, residing at Cincinnati, in the county of Hamilton and State of Ohio, have invented a new, original, and ornamental Design for Soda-Fountains and Ice-Cream-Dispensing Apparatus, of which the following is a specification, reference being had to the accompanying sheet of drawings, forming part thereof.

In the accompanying sheet of drawings, aforesaid, Figure 1 is a perspective view showing the fountain and ice-cream dispensing apparatus embodying my new and original design, and Fig. 2 is an end elevation of the same.

I claim:—

The ornamental design for a soda fountain and ice-cream dispensing apparatus, as shown.

WILLIAM F. BEATTY.
